UNITED STATES PATENT OFFICE

BERTRAM C. HAMM, OF CAMBRIDGE, MASSACHUSETTS

DESK ADJUNCT

Application filed June 24, 1929. Serial No. 373,099.

This invention relates to a desk having a top, and a thin slide movable in a guideway under an end portion of the top and usually between the top and an upper drawer, the slide being adapted to be retracted and stored under the top, and projected therefrom for use, and adapted to serve as a support for articles laid on its upper surface when the slide is projected.

The object of the invention is to enable the slide to serve also as a holder intended to be frequently consulted by the user of the desk, said cards being for example, leaves of a card index, the construction of the slide being such that the cards are movable with the slide to retracted and projected positions, the slide and cards supported thereby constituting a desk adjunct having two functions, one of which is to support articles laid on the slide when it is projected, and the other to enable the user of the desk to conveniently manipulate and inspect the cards.

Of the accompanying drawing forming a part of this specification,—

Figure 1 is a perspective view of a portion of a desk and a slide the latter being shown by dotted lines in its projected position.

Figure 2 is a fragmentary section on line 2—2 of Figure 1, the slide being shown in its projected position and provided with cards.

Figure 3 is a perspective view, showing the slide provided with a displaceable top.

Figure 4 is a section on line 4—4 of Figure 3.

Figure 5 is a fragmentary sectional and perspective view, showing a portion of the slide and portions of cards engaged therewith.

Figures 6 and 7 are perspective views of the adjunct, showing different arrangements.

The same reference characters indicate the same parts in all of the figures.

In the drawing, *a* designates a desk top, below an end portion of which is a runway

b, located between the top and an upper drawer *c*, the described construction being common and well known, the runway being formed to guide a relatively thin slide to a retracted position and to a projected position.

In carrying out my invention I provide a slide movable in the runway *b*, and comprising a bottom portion 12, side walls 14, and end walls 15, each upstanding from the bottom, said bottom and walls defining an upwardly opening recess in the slide. In other words, the slide is formed as a shallow drawer formed to move in the runway and adapted to contain cards 16, and permit displacement and inspection of the same when the slide is projected.

Each card bears at one end on the bottom, and is inclined so that its opposite end is above the bottom and within the recess, to permit the housing and projection of the cards with the slide, the cards being in overlapping relation to each other, as shown. Each card 16 is adapted to be displaced upwardly from a card normally overlapped thereby. Loose cards 16a may be interposed between the overlapping cards 16.

It will be seen that the recessed slide is adapted to confine the cards against horizontal displacement, and to permit upward displacement thereof, so that the user may conveniently inspect indicia associated with the cards.

It will also be seen that the cards 16, when arranged in overlapping relation, are adapted to support articles laid loosely on the slide, although if desired, the slide may be provided with a movable top 18, adapted to cover the cards 16, as shown by Figures 3 and 4. Said top is, in this instance, movable in grooves in the walls 15.

The slide may have an extension 12a, projecting inwardly from the inner wall 15, as shown by Figures 2, 3 and 4, so that the slide is sufficiently supported when projected, to

fully expose the recess and the cards therein. Said extension may have a stop member 12b, adapted to abut a fixed stop member 12c, when the slide is fully projected.

5 The cards 16 may be arranged to extend lengthwise of the slide, as shown by Figures 2, 3, 4, 5 and 7, or crosswise of the slide, as shown by Figure 6.

10 The slide recess may be formed in a plurality of parts separated from each other by transverse partitions 19, so that the adjunct may include a plurality of sets of cards 15, as shown by Figure 6.

15 The cards 16 may be connected at their inner ends with the slide in any suitable way, as by ribs 21 on the walls 14, engaging notches 22 in the cards, as indicated by Figure 5.

20 It will be seen that the side surfaces of the cards may bear any suitable informative indicia, and that they collectively present an informative area much greater than that of the slide, so that the desk user may, while in the usual desk-using position, and without moving therefrom, obtain a wider range 25 of information than would be otherwise obtainable.

I claim:

30 An office desk of the type used by a person in a seated position having superposed drawers beside the position occupied by the seated user of the desk, and a slide arranged between the desk top and the uppermost one of such drawers adapted to be either pulled out and serve as a support or to be pushed 35 in under the desk top out of the way, distinguished by the fact that in place of such slide is substituted a shallow drawer of substantially the same dimensions as the slide adapted to occupy the recess provided for 40 the slide and to be pulled out and pushed in, combined with cards or the like occupying the drawer in overlapping relationship, adapted to be raised for inspection of matter noted on the cards, but when lying in normal 45 position being wholly contained within the interior space of the drawer.

In testimony whereof I have affixed my signature.

BERTRAM C. HAMM.
